CLAIM

The ornamental design for a transceiver module for a table-top teleconferencing system, as shown and described.

DESCRIPTION

FIG. 1 is a perspective view of a transceiver module for a table-top teleconferencing system showing our new design;

FIG. 2 is a typical side elevational view thereof;

FIG. 3 is a top plan view thereof; and,

FIG. 4 is a bottom plan view thereof.

FIG. 1.

FIG. 3.

FIG. 2.

FIG. 4.
